UNITED STATES PATENT OFFICE.

SAMUEL V. ESSICK, OF ALLIANCE, OHIO, ASSIGNOR OF ONE-HALF TO AMOS W. COATES, OF SAME PLACE.

TELEGRAPHIC TRANSMITTER.

SPECIFICATION forming part of Letters Patent No. 250,138, dated November 29, 1881.

Application filed July 26, 1881. (No model.)

To all whom it may concern:

Be it known that I, SAMUEL V. ESSICK, of Alliance, county of Stark, State of Ohio, have invented new and useful Improvements in Telegraphs, of which the following is a full, clear, and exact description, reference being had to the accompanying drawings, making part of this specification, in which—

Figure 1 is a perspective view of my improved telegraphing apparatus. Fig. 2 is a plan or top view, and Fig. 3 a vertical longitudinal section, through the same. Fig. 4 is a vertical section through the alphabet-cylinder, showing one of the sliding tappets in position to be operated thereby; and Fig. 5 is a perspective view of one of the sliding tappets.

My invention relates to a novel mechanism for automatically forming the dots and dashes of what is known as the "Morse" system of telegraphing, or any analogous thereto, through keys conforming in number to the number of letters, and other characters employed in said system for designating the different letters of the alphabet, numerals, &c.; and it consists in the employment of a cylinder, or equivalent device, provided on its face with a series of ribs, raised surfaces, or projections, with intervening depressions arranged in circles on the cylinder, the raised surfaces in any one of the series of broken rings or circles conforming to the dots and dashes of a letter or character of the alphabet, said cylinder being operated by clock mechanism or any convenient or suitable power, and acting through suitable tappets, levers, &c., as hereinafter described, to close and break the line-wire circuit.

In the accompanying drawings, A A' A², &c., represent a frame-work of metal, A representing the base, and A' A², &c., uprights and arms forming suitable supports for the mechanism, and serving as conductors, arranged within the circuit of the line-wire of the telegraph, as follows: One of the inclined arms, A², has a binding-post, a, attached to it, through which connection may be made with the battery or battery and ground wire, and upon the outer ends of the arms A² is secured a transverse bar, A³, suitable insulators (indicated at b) being interposed between said bar and the arm A², so as to break the connection between them. The

bar A³ has a binding-post, a', to which the line-wire is to be attached.

In suitable bearings in the frame-posts, at c, is mounted a shaft carrying a cylinder, D, which is provided on its surface with a series of broken rings, ribs, or raised surfaces, the number in said series corresponding to the number of characters contained, say, in what is known as the "Morse" alphabet, or any equivalent thereof, representing the different letters, numerals, &c., the projections in each of said series of rings or ribs conforming to the dots and dashes employed in representing said letters, one for each letter, &c. Thus each ring or broken peripherical rib on the cylinder is composed of a series of short projections, d, or long ones, d', or of a combination of the two, conforming to the dots and dashes of the letters or other characters represented, the short rises representing the dots, and the long ones the dashes of the letter, the recesses between the projections forming the spaces between the dots and dashes.

Upon one end of this cylinder, or upon the shaft carrying it, is secured a gear-wheel, D', through which a rotary motion is imparted to it, whenever the cylinder is tripped or left free to rotate, by means of any suitable mechanism—such, for example, as an ordinary clock mechanism actuated by spring or weight, or by any suitable or convenient power.

The cylinder D is provided with a locking spur or cam at d², near one end, or one at each end, if desired, which engages with a spur or shoulder at e', on an arm or lever, E, for locking the cylinder against the action of its driving mechanism and preventing its rotation. The arm or lever E is made in loop or bail form, the arms e e of which, at their forward ends, are pivoted to the frame-bars A² at f f, as shown, and passing thence underneath the cylinder, are connected at their rear ends by the transverse portion of the bail, arranged in rear of the cylinder and parallel with the shaft thereof. The arms of said bail may either be made springs to uphold the bail for causing it to engage the cylinder, in which case the forward ends of said arms will be readily connected with the frame, or they may be pivoted, as stated, and a spring or springs of any suitable

ble form applied for upholding them in engagement with the cylinder.

Upon a transverse rod, *g*, secured in arms *A*⁴ of the frame-bars *A*², is pivoted a number of 5 longitudinal bars, *h h*, corresponding in number to the number of letters or sectional ribs on the cylinder *D*, said bars extending back over the cylinder and terminating at their rear free ends underneath the bar *A*³, and upon the 10 bars *h* are arranged sliding tappets *h'*, adapted to be moved longitudinally on the bars *h*, for bringing a pendent spur, *i*, thereon into position to be acted upon by the broken ribs or projections on the cylinder *D*, and thereby to raise 15 the respective bars with which they are connected into contact with the binding-post bar *A*³, and thus close the circuit.

The tappets *h'* are moved into position to be acted upon by the cylinder by means of *L*-shaped levers *J*, there being one of said levers 20 for each tappet. These levers consist of a longitudinal arm or bar extending from the forward end of the machine-frame to near the rear end thereof, being pivoted at their rear 25 ends on a transverse rod or shaft at *k*, and of a vertical arm, *J'*, rising above said pivot to the plane, or nearly so, of the bars *h*, said vertical arms being provided at their upper ends with short forwardly-projecting arms *j*, which 30 rest in contact with the rear face of the sliding tappet-blocks *h'*.

The forward ends of the levers *J* have vertical rods *l* pivoted to them, said rods passing up through a perforated guide or key-board, (indicated at *M*.) and are provided at their upper ends with knobs or keys *L*, which may be lettered, numbered, &c., to correspond with the respective sectional ribs on the cylinder representing the different letters, characters, 35 &c., of the Morse alphabet. It will be seen that by pressing down on these knobs or keys the spurs or arms *j* on the upper ends of the arms *J'* will be thrown forward, and thus made to move the sliding tappet-block into position 40 to be acted upon by the rises or projections on the cylinder, where it remains until the cylinder has made one revolution. The arms *J'* are each provided with a forwardly-projecting spur, *j'*, which overhangs the transverse bar of the 45 tripping bail or lever *E*. Said spur is provided with an inclined or cam-shaped lower face, and by preference the upper face of the bail *E* is also correspondingly inclined, the one resting upon and in contact with the other, so that as 50 the arm *J* is vibrated to move the tappet into position to be acted upon the spur *j'* wedges the bail downward, throwing the spur or shoulder thereon out of engagement with the cylinder, and permitting the latter to rotate.

55 For throwing the tappets out of action the cylinder is provided with a series of spurs, *n*, on its periphery, intermediate between the circles of risers indicating the dots and dashes referred to.

60 Each sliding tappet-block is provided on one side with two pins, *p p'*, and the lower end of

a pendent lever, *Q*, rests between these pins. The levers *Q* are pivoted upon a transverse rod *g*, and, extending above said pivot, have their upper ends connected at *q'* with pendent 70 levers *R*, also pivoted to a transverse rod, *r*, and pendent therefrom. These pendent levers *R* are slightly curved, as shown, so as to pass down in rear of the pivotal rod *q*, from which point they curve slightly forward, their lower 75 ends resting upon the cylinder *D*, or in close proximity thereto, between the sectional rings or ribs representing the letters, so that said ends will be struck and moved forward by the spur *n* just as the cylinder is completing 80 its revolution. The arrangement is such that as the pendent lever *R* is vibrated forward it carries forward with it the upper end of lever *Q*, causing the lower end of said lever, and with it the tappet-slide, and the upper end 85 of arm *J'* of the lever *J*, to be moved back, throwing the tappet back out of working relation to cylinder *D*. When the cylinder has completed its full revolution it is stopped by means of the bail *E*, the pawls or shoulders on 90 the latter rising into engagement with and locking said cylinder against further rotation until it is again tripped or released by the depression of one of the keys *L*, as explained.

95 By the arrangement of mechanism described it will be seen that the sending of a message is made purely mechanical, it being apparent that it is necessary only that the operator shall be familiar with the keys upon which the different letters and characters represented 100 may be plainly indicated, in order to transmit a message with a rapidity limited only by his skill in manipulating the keys, as the cylinder may be made very light and adapted to rotate with any desired velocity. The message may, 105 of course, be received in any usual or preferred manner, the action of the receiving-instrument being precisely the same as where the "dots and dashes," so called, are formed by hand in the ordinary manner, while only one movement of 110 a key being required to form any one letter or other character employed instead of several, as when made by the finger of the operator, the rapidity with which a message can be sent will be correspondingly increased.

115 It will be apparent that the construction of the apparatus or machine in the form and arrangement of its parts may be varied without departing from my invention, and I therefore do not wish to be confined to the specific form 120 and arrangement of parts shown in describing how the invention can be carried out in practice.

Having now described my invention, I claim—

125 1. In an automatic telegraph, a cylinder, and means for rotating the same, said cylinder having raised surfaces, in combination with pivoted bars provided with tappet-blocks or their equivalent, levers for throwing the tappet-blocks on said bars into position to be acted upon by said cylinder, devices connecting said

levers to the cylinder, as described, and keys to actuate said levers, whereby the cylinder is tripped and permitted to revolve at the same time that the tappet-block selected is thrown 5 into position to be actuated by the cylinder, as and for the purpose set forth.

2. The combination, in an automatic telegraph, of a cylinder provided with a series of broken annular ribs or raised surfaces, corresponding to the letters of the Morse alphabet, or analogous thereto, adapted to act as cams, a series of levers, one for each letter and operated thereby, a series of tappet-blocks adjustable on said levers, and means for throwing 15 said blocks into and out of operation, substantially as described.

3. In an automatic telegraph, a cylinder and devices to rotate the same, said cylinder being provided with raised cams, in combination with 20 tappet-bars for closing the circuit, means, substantially as described, for automatically arresting and holding said cylinder at the end of each revolution, and tripping devices, as described, whereby said cylinder is released from 25 said holding devices and any one of the tappet-bars thrown into action simultaneously therewith, substantially as and for the purpose set forth.

4. In an automatic telegraph, a cylinder, and 30 means for rotating the same, said cylinder being provided with raised surfaces, in combination

with the tappets and tappet-bars for closing the circuit, means, substantially as described, for automatically and simultaneously throwing said levers and tappets out of action, 35 and means for arresting the rotation of the cylinder, substantially as described.

5. The cylinder provided with raised surfaces corresponding to the dots and dashes of the Morse alphabet, or its equivalent, and with 40 tripping-spurs, in combination with levers for throwing the movable tappets out of action upon the completion of a letter, or at the end of each revolution of the cylinder, substantially as described. 45

6. The combination, in an automatic telegraph, of the cylinder, with its raised surfaces, in the form of the dots and dashes of the Morse alphabet, or its equivalent, the tappet-bars acted upon thereby for closing the circuit, keys 50 and mechanism for tripping the cylinder and throwing the tappets into action, mechanism for actuating the cylinder, and mechanism for stopping the cylinder upon the completion of each letter, substantially as described. 55

In testimony whereof I have hereunto set my hand this 19th day of July, A. D. 1881.

SAMUEL V. ESSICK.
